CLAIM

The ornamental design for a combined bottle and bottle cap, as shown and described.

DESCRIPTION

FIG. 1 is a perspective view of a combined bottle and bottle cap;

FIG. 2 is a front view of the combined bottle and bottle cap;

FIG. 3 is a rear view of the combined bottle and bottle cap;

FIG. 4 is a right side view of the combined bottle and bottle cap;

FIG. 5 is a left side view of the combined bottle and bottle cap;

FIG. 6 is a top view of the combined bottle and bottle cap; and,

FIG. 7 is a bottom view of the combined bottle and bottle cap.

The broken lines illustrate portions of the combined bottle and bottle cap, and form no part of the claimed design.

1 Claim, 6 Drawing Sheets
